H. H. DIEHL

RAILWAY FROG AND METHOD OF MANUFACTURING SAME

Filed Oct. 1, 1923

UNITED STATES PATENT OFFICE.

HERMAN H. DIEHL, OF HUNTINGTON, WEST VIRGINIA, ASSIGNOR TO THE WEST VIRGINIA RAIL COMPANY, OF HUNTINGTON, WEST VIRGINIA, A CORPORATION OF WEST VIRGINIA.

RAILWAY FROG AND METHOD OF MANUFACTURING SAME.

Application filed October 1, 1923, Serial No. 666,009.

To all whom it may concern:

Be it known that I, HERMAN H. DIEHL, a citizen of the United States, residing at Huntington, in the county of Cabell and 5 State of West Virginia, have invented a new and useful Improvement in Railway Frogs and Methods of Manufacturing Same, of which the following is a specification.

My invention relates, more particularly, to 10 the points of frogs which comprise the portion thereof which presents the angularly-disposed rail sections which converge toward, and terminate in, an apex or point.

Steel frog-points as hitherto constructed 15 involve the bending and machining of certain portions of the rails used to form the frog-point, which are expensive operations to perform, and furthermore the extreme apex portion of the frog-point, and which 20 is subjected to very severe stresses in use, due to impacts produced by the wheels of the vehicle traversing the frog, often becomes impaired and sometimes breaks, rendering the frog unsuited, if not unfit, for further 25 use.

One of my objects is to provide for the 30 production of frog-points at less cost than hitherto possible; another object is to provide improvements in frog-points to the end 35 that they will be better adapted to withstand the stresses to which they are subjected in use, reducing to the minimum danger of impairment thereof whether by deformation, due to the pounding of the wheels against 40 the apex portion of the frog-point; through breakage of the point by the action of the wheel; or the destruction of the point by reason of the looseness of its two component parts relative to each other which feature commonly results in the usual two-piece 45 frog-point constructions; and other objects as will be manifest from the following description.

Referring to the accompanying drawings: 50 Figure 1 is a plan view of the frog-point, showing its condition during the process of forming it in accordance with my invention. Figure 2 is a plan sectional view of the frog-point, the section being taken as represented 55 at the line 2 on Fig. 3 and viewed in the direction of the arrow. Figure 3 is a section taken at the line 3 on Fig. 1 and viewed in the direction of the arrow. Figure 4 is a view like Fig. 3 of the completed frog-point,

Figure 5 is a plan view, with one end broken 55 away, of the blank from which the frog point of the preceding figures is formed; and Figure 6, a section taken at the line 6 60 on Fig. 5 and viewed in the direction of the arrow.

In producing my improved structure in the preferred way, I form the frog-point from a single section of steel rail of the desired gauge, the head of the rail at opposite sides thereof, and one base flange of 65 the rail, being cut away at points midway between the ends of the rail, as represented at 10, 11 and 12, these cut-away portions each presenting the converging surfaces, as represented at 13, 14 70 and 15, respectively, the points at which the converging surfaces 13 and 15 intersect lying in the same plane transversely of the rail, and the surfaces 13 being more divergent than the surfaces 14, as shown. The rail thus 75 conditioned is then bent at the point midway of its length in a direction to cause the surfaces 13 and 14 to approach each other, respectively, and to an extent sufficient to cause these opposed surfaces to extend into 80 close proximity to each other, the surfaces 13, 14 and 15 extending at such angles relative to each other and to the plane of the rail that when the rail is bent as above stated the outer ends of the diverging rail 85 portions of the frog-point will extend, relative to each other generally, substantially at the desired angle.

Following the bending of the rail as 90 stated the web and head portions of the rail at the apex portion of the frog-point are subjected to an operation, preferably a squeezing or swaging operation for affording to the extremity of the apex portion, the desired form such as that shown in 95 Figs. 1 and 2 and inwardly deflecting the web and head portions of the rail and the outer flanges thereof at the apex portion to cause the web and head portions to occupy the positions represented in Figs. 1 and 2, 100 wherein the web portions extend into close proximity to each other as shown.

In the finished structure the outside vertical edges of the diverging head-portions of the frog at the apex portion of the frog-point will extend at the same angle as the body portions of these rails and in the same 105 lateral planes as the vertical outer surfaces

of the heads of the rail portions of which they are continuations as shown in Fig. 1, and such shape is given to the structure by the operation above referred to. Also in 5 the finished structure the outside edges of the outer flanges of the frog-point, at the apex portion of the frog-point, are in line with the corresponding edges of these flanges in the rear of said apex portion, as shown 10 in Figs. 1 and 2, this being accomplished in any desirable way as, for example, by planing the edges of these flanges.

In accordance with the preferred way of 15 producing the frog point, the diverging rail portions thereof, at the apex portion of the frog-point, are united preferably by electrically arc-welding them at the joint therebetween. As shown in the drawings, this welding is provided only along the joint 20 at the upper surface of the head portions of the frog-point, but it will be understood that where conditions render it desirable the joint between the opposing base flange portions of the frog-point may be welded together. Preliminary to the welding operation 25 referred to it is preferred that the metal at the opposite sides of the joint referred to be cut away, as represented at 16, to provide a welding-flux-receiving channel at 30 which the welding is to be effected. This channel which is preferably formed after bending the rail and shaping the bent rail as above stated, preferably extends throughout the length of this joint thus opening 35 through the extremity of the apex of the frog-point as shown, and this is especially desirable where, in accordance with the preferred way of producing the frog-point, the flux employed is of manganese steel, inasmuch as thereby the finished frog-point 40 is caused to present, throughout the portion thereof which is subjected to the greatest wearing stresses in use, the body of metal, represented at 17, presenting high resistance 45 to wear and breakage.

By manufacturing a frog-point in accordance with my invention the structure may not only be more economically produced but it is capable of resisting to a high 50 degree the stresses to which this part of a frog-point are subjected in use, it being noted that the diverging portions of the frog-point serve to reinforce each other, at the apex of the frog-point, against side blows which 55 have a tendency to break off the apex portion thereof, but which breakage is prevented by the reinforcement referred to. Furthermore, by providing the body of manganese steel at the upper surface of the 60 apex of the frog-point, this apex portion is not only more resistant to pounding stresses directed downwardly against it in use, but is rendered more rigid to resist side blows.

In use my improved frog point may be 65 provided either as a structure separate from

the other parts of the frog and assembled with such other parts at the location of the frog in the track, in any suitable way, or connected with some or all of such other parts, as, for example, by a plate, to form 70 a unit, to facilitate its application to, and removal from, the desired position in a track.

While I have described a particular construction of frog-point, I do not wish to be 75 understood as intending to limit the invention thereto, as variations in the manner of producing the frog-point may be practiced and the construction of the frog-point 80 variously modified and altered, without departing from the spirit of my invention.

What I claim as new, and desire to secure by Letters Patent, is:

1. A frog-point formed of integral diverging steel-rail portions, with the metal of opposing portions, at the apex portion of the frog-point, united. 85

2. A frog-point formed of integral diverging steel rail portions, with the joint between opposing portions, at the apex portion of the frog-point, welded. 90

3. A frog-point comprising integrally diverging rail portions formed from a rail bent at a point between its ends with the joint between opposing portions of the rail adjacent the apex portion thereof, welded with a material more resistant to the forces to which the frog-point is subjected in use, than the material comprising the rail from 95 which the frog-point is formed. 100

4. A frog-point comprising integral diverging rail portions formed from a rail bent at a point between its ends, with the joint between opposing portions of the frog-point, adjacent the apex portion thereof, welded with a material more resistant to the forces to which the frog-point is subjected in use, than the material comprising the rail from 105 which the frog-point is formed, the material constituting the weld extending 110 substantially to the extremity of said apex portion.

5. A frog-point formed from a rail bent midway its ends and provided at the upper 115 surface of its apex portion with an inset body of material more resistant to the forces to which the frog-point is subjected in use, than the material comprising the body of the frog-point.

6. A frog-point formed from a rail bent midway its ends and provided at the upper surface of its apex portion with an inset body of material more resistant to the forces to which the frog-point is subjected in use, than the material comprising the body of 125 the frog-point, said inset body extending substantially to the extremity of said apex portion.

7. A blank from which to form a frog-point, comprising a member of the same 130

cross-sectional shape as a rail, the head thereof being recessed at opposite sides along converging lines one of its base flanges being straight and the remaining one of its base

5 flanges being recessed along converging lines at a slight angle to the sides of said recess in the head at the corresponding side of the member.

8. A frog-point comprising integral diverging rail portions formed from a steel rail bent at a point between its ends and having its web portions adjacent the extremity of the apex of the point compressed and extruded into a homogeneous body with the 10 head of the rail with the base flanges in continuous contact, thus affording to the structure the stability and shock-resisting properties of two webs.

9. A frog-point formed of a single length 20 of steel rail, bent at a point between its ends with the joint between opposing portions of the rail, adjacent the apex portion thereof, welded, whereby the diverging rail portions present substantially the same strength and 25 stiffness as in the case of a solid, one-piece, frog-point.

10. A blank from which to form a frog-point comprising a member of the same cross-sectional shape as a rail, the head 30 thereof being recessed at one side along converging lines and the base flange thereof at the same side as the recess in said head being recessed, the walls of said recessed portion

of said base flange where they extend laterally beyond said head converging at a lesser 35 angle than the walls of the recess in said head.

11. A blank from which to form a frog-point, comprising a member of the same cross-sectional shape as a rail, the head 40 thereof being recessed at one side along converging lines and the base flange thereof at the same side as the recess in said head being recessed along converging lines, the outer ends of which extend at a lesser angle 45 to each other than the inner ends of said lines.

12. A blank from which to form a frog-point comprising a member of the same cross-sectional shape as a rail, the head 50 thereof being recessed at opposite sides along converging lines and one of the base flanges thereof being recessed along converging lines, the outer ends of which extend at a lesser angle to each other than the inner ends 55 of said lines.

13. A blank from which to form a frog-point comprising a member of the same cross-sectional shape as a rail, the head 60 thereof being recessed at opposite sides along converging lines, and one of its base flanges being recessed along converging lines at a slight angle to the sides of said recess in the head at the corresponding side of the member.

HERMAN H. DIEHL.
